MIRROR OR THE LIKE

Meyer Barlow, Nassau County, N. Y., assignor to Marsel Mirror & Glass Products, Inc., Brooklyn, N. Y., a corporation of New York

Application January 3, 1955, Serial No. 33,780

Term of patent 7 years

(Cl. D33—9)

Fig. 1 is a front perspective view of a mirror or the like showing my new design; and

Fig. 2 is a fragmentary elevational view thereof.

I claim:

The ornamental design for a mirror or the like, as shown.
